METHOD AND APPARATUS FOR PRODUCING
CRIMPED STAPLE FIBERSFrederick William Koster and Alexander
Bruenner, Meadville, Pa., assignors to Ameri-
can Viscose Corporation, Wilmington, Del.,
a corporation of Delaware

Application August 13, 1941, Serial No. 406,706

6 Claims. (Cl. 19—66)

1

It is an object of the invention to provide a method of producing crimped staple fibers in accordance with which the crimping is performed substantially simultaneously with the cutting of the continuous filaments to staple and in accordance with which the crimping and the cutting are performed in such a manner that all the staple fibers have substantially the same length independent of any differences of crimping of the individual fibers.

A further object of the invention is to provide a novel apparatus adapted to carry out the method in a commercially practical way. Further objects of the invention will appear from the drawing and the description thereof which follows.

In the drawing, illustrative of the invention, Figure 1 is an elevational view of the apparatus in cross-section taken on lines I—I of Figure 2,

Figure 2 is a sectional view taken on lines II—II of Figure 1,

Figure 3 is a cross-section taken on lines III—III of Figure 1.

Essentially, the method of the invention comprises the feeding of a bundle of relatively un-twisted filaments into a cutting device and applying a crimping agent to the filament bundle upon the discharge side of the cutting device. By the expression "crimping agent" is meant any substance or medium the immediate application of which effects a crimped or curly state in the cut filaments or staple fibers, the expression being applied hereinafter only to the substance or medium which brings out substantially directly and immediately the crimped condition even though it may be necessary in certain cases for the so-called crimping agent to function in co-operation or in combination with some other ingredient or agent incorporated in or coated upon the filaments prior to the application of the so-called crimping agent. Similarly, the expression "crimping agent" is employed regardless of the particular mechanism involved in producing the crimped condition, whether it be the irregular expansion or shrinkage of the fibers, the irregular evaporation or other form of removal of certain ingredients in the filaments, etc. In the simplest embodiment, a heated fluid medium, preferably steam or hot air, acts as an effective crimping agent for cellulose acetate filaments. The invention is applicable to other artificial filaments of different constitution, such as regenerated cellulose from cuprammonium cellulose or from viscose solutions, other cellulose esters and cellulose ethers, filaments of casein, of polyvinyl resins, such as chlorinated and unchlorinated

2

polyvinyl chloride or chlorinated or unchlorinated co-polymers of vinyl chloride and vinyl acetate. Steam or hot air or mixtures thereof may be employed as the crimping agent for any of these filaments of different constitutions, but other crimping agents may be selected for use with any of these filaments, the agent selected depending upon its adaptability and suitability with respect to the particular nature of the filaments.

10 In accordance with the method of this invention, care is taken to prevent the crimping agent from exerting any substantial crimping effect upon any portion of the filament bundle until it is being cut therefrom thereby preventing the 15 cutting of unequal lengths of staple fiber. In this way, the crimping agent acts upon the fibers substantially at the time of their severance whereby the crimping effect is enhanced by virtue of any irregularities or stresses imparted to 20 the fiber structure at the time of cutting and before such irregularities or stresses are permitted to undergo any equalization or compensation that might occur during subsequent treatment processes. Furthermore, by applying the crimping agent simultaneously or practically simultaneously with the cutting of the staple fibers, there is a strong tendency to separate the fiber bundles into individual filamentary fibers and therefore the amount of working necessary to be applied to the fibers in order to open them properly is greatly reduced and in many cases may be entirely eliminated. The application of the crimping agent to the fibers as they are being severed from the main filament bundle appears 30 therefore not only to effect crimping of the fibers but also to open them up. In some cases, the crimping agent may also serve to assist the feeding of the filaments into the cutting means as will be more particularly described hereinafter 35 40 with reference to the particular apparatus shown in the drawing.

The condition of filaments as they are fed to the cutter is not a critical matter. For example, they may be in a completely dry and finished 45 state of manufacture or they may still contain some of the solvent with which they were spun. For example, cellulose acetate filaments may still contain a small proportion of acetone or other solvent at the time they are fed to the cutters 50 and the rapid evaporation of such solvent from the filaments effected by the hot air or steam accentuates the crimping effects obtainable thereby. The filaments of other constitution may also contain a small amount of their respective 55 solvents at the time they are fed to the cutting

device and in the case of viscose, it may be fed to the cutters while in a condition of incomplete regeneration. If desired, special ingredients common in the art may be added to the spinning bath so that these ingredients are contained in the filaments that are spun therefrom and enhance or assist the crimping effect subsequently obtained at the time of application of the crimping agent. These known ingredients just referred to (not to be confused with the term "crimping agent" as used in this specification) are commonly called crimping agents in the art though they exert their crimping effect at a late stage in the formation of the spun filament and frequently only with the cooperation of a second specific agent (this latter agent falling in the definition of crimping agent herein). When such ingredients are employed in this process, it is preferred to feed the filaments to the cutter before these agents or ingredients have exerted any substantial crimping influence to prevent any irregularity in the length of the staple fibers produced.

After their production in accordance with this process, the staple fibers may be sprayed with any finish customarily applied during their passage away from the cutting and crimping device, or they may be treated in accordance with any customary or desired process adapting them to any particular use.

The drawing shows one form of apparatus particularly suitable for carrying out the method of the invention. The apparatus disclosed in the drawing comprises a feeding disc 2 for feeding filaments to the cutting knife 3 and disc 4. The disc 2 is provided with a funnel-like filament entrance 5 which is connected with a radial discharge opening 6. The disc 2 is also provided with a shaft 7 by which it is adapted to be rotated by a suitable motor not shown. The disc 2 is enclosed in casing 8 which is provided with a cover plate 9 and which is formed integrally with a channel 10 extending tangentially of the annular spacing between the casing and the disc 2 therein. The casing is provided with openings 11 and 12 which permit the cutting knife 3 and disc 4 to extend into cutting relationship adjacent the periphery of the disc 2. The channel 10 is also provided at its top with a nozzle 13 into which the crimping agent, such as steam or hot air, may be directed by the pipe 14. A discharge duct 15 is attached to the open lower end of the channel 10.

The cutting knife and disc 4 are mounted to be driven by intermeshing gears 16 and 17 which are driven by a motor (not shown) through the gear 18. The disc 4, which acts as an anvil, may be an idler, in which case, gear 17 is omitted. Disc 4 may be substituted by a knife, if desired.

In operation of the apparatus, the filament or filament bundle is fed (with or without the assistance of an air jet) into the funnel mouth 5 of the disc 2 and passes through its radial channel 6 by virtue of the centrifugal force developed by rotation of the disc and is directed into the nip of the cutting blade 3 and disc 4 once every revolution of the disc. The crimping agent, suitably steam under a pressure of 30 to 40 lbs. per square inch, is continuously blown through the nozzle 13 transversely of the filaments as they are being severed, directing the severed and crimped fibers through the passage 10 into the discharge duct or pipe 15. It will be seen from the drawing that in this arrangement the knife 3 and disc 4 act as a barrier to prevent any substantial

amount of the crimping agent from coming into contact with the filaments on the feeding side of the knife 3 and disc 4 so that the fibers cut therefrom have a substantially unvarying length which depends upon the speed of rotation of the disc 2 and the rate of feed of the filament bundle to the disc. While the arrangement of the nozzle 13, knife 3 and disc 4 is preferably as shown, it is not essential that the crimping agent be entirely excluded from contact with the filament bundle entering the bite of the knife 3 and disc 4 provided the radial velocity of the filament bundle is sufficiently rapid so that the agent has insufficient time to effect crimping before cutting or the centrifugal force upon the filaments holds them under sufficient tension to prevent any substantial manifestation of the crimping effect prior to cutting. The radial distance from the peripheral surface of the disc 2 to the interior of its casing may be varied and designed to accommodate any desired length of fiber to be produced. In addition the casing may have the general form of a spiral, in which the cross sectional area surrounding the disc 2 increases in the direction of rotation of the disc to a maximum at the approach of the bite of knife 3 and disc 4.

There may be employed other arrangements of the nozzle for supplying the crimping agent in any desired direction to the staple fibers as they are cut. However, the arrangement of the nozzle in the embodiment shown in the drawing is such that the passage of the crimping agent at high velocity transversely of the staple fiber portion of the filament bundle and substantially tangentially of the disc 2 in the direction of its rotation creates a certain amount of reduced pressure in the upper portion of the annular space surrounding the disc 2 and in this fashion reduces the air resistance encountered by the filaments protruding from the conduit 6 as they approach the knife 3 and disc 4. This action tends to assist the directing of the filaments into the bite of the knife 3 and disc 4 and to overcome any tendency to drag by virtue of air resistance. Besides effecting crimping of the fibers, the blast of steam tends to open up any clumps of fibers.

If desired, the jet of crimping agent may be intermittently applied at the instants of cutting successive bunches of fibers from the filament bundle. Instead of a single jet, a plurality of spaced jets may be substituted and they may be made to discharge parallel streams or crossed streams of crimping agent. By adjusting the point of intercrossing of two or more such streams with respect to the position of the fiber bundle as it is being severed and by adjusting the strength of the several streams of crimping agent, any desired degree of turbulence or, indeed, freedom from turbulence, may be obtained within the channel 10, thereby enabling the operator to obtain the desired extent of opening of the fiber bundles with any desired degree of rapidity for any given type of fiber.

The drawing and the description thereof is intended to be illustrative only and various modifications and changes may be made therein without departing from the spirit and scope of the invention as defined in the appended claims.

We claim:

1. In a method of producing crimped staple fibers from filaments, the steps of rotating an end portion of the length of said filaments about an axis at right angles to said portion to effect feeding of said filaments radially outwardly from

5

said axis, periodically cutting the outermost portion of said filaments at a position some distance from said axis, and directing a heated fluid crimping agent transversely of said filaments at their cutting position and tangentially in the same direction as the direction of rotation of said end portion whereby said fluid tends to reduce the air resistance against said end portion as it approaches said cutting position.

2. An apparatus for producing crimped staple fibers from filaments comprising a disc having an axial bore interconnected with a radial bore, means for rotating said disc, cutting means adjacent the periphery of said disc, a channel on the other side of said cutting means substantially tangential of said disc, and means for supplying said channel with a fluid crimping agent.

3. An apparatus for producing crimped staple fibers from filaments comprising a disc having an axial bore interconnected with a radial bore, means for rotating said disc, cutting means adjacent the periphery of said disc, a channel on the other side of said cutting means substantially tangential of said disc, and a nozzle in said channel for directing a stream of fluid longitudinally therethrough.

4. An apparatus for producing crimped staple fibers from filaments comprising a disc having an axial bore interconnected with a radial bore, means for rotating said disc, a casing surrounding said disc, a space between said disc and casing, said casing comprising a substantially tangentially extending channel, cutting means adjacent the periphery of said disc nearest said channel, and a nozzle in said channel directing a stream of fluid longitudinally therethrough.

5. An apparatus for producing crimped staple fibers from filaments comprising a disc having an

6

axial bore interconnected with a radial bore, means for rotating said disc, a casing surrounding said disc, a space between said disc and casing said casing comprising a substantially tangentially extending channel, cutting means adjacent the periphery of said disc nearest said channel, and a nozzle in said channel directing a stream of fluid longitudinally through said channel, a discharge opening in said channel opposite said nozzle and means for supplying said nozzle with steam.

10. composite said nozzle and means for supplying said nozzle with steam.

15 6. An apparatus for producing crimped staple fibers from filaments comprising a disc having an axial bore interconnected with a radial bore, means for rotating said disk, cutting means adjacent the periphery of said disk, a channel on the other side of said cutting means, and means for supplying said channel with a fluid crimping agent.
